QUILL BRUSH HOLDER

Martin Perr, Newark, N. J., assignor of one-half to William H. Robinowitz, Newark, N. J.

Application April 16, 1937, Serial No. 137,217

2 Claims. (Cl. 279—50)

This invention relates to improvements in artists' and sign painters' brushes; and the invention has reference, more particularly, to an improved brush holder adapted for the interchangeable connection therewith of quill brushes of various sizes.

The invention has for an object to provide a brush holder having a simple, efficient and easily manipulated means for detachably coupling thereto quill brushes; the novel coupling arrangement being such that the quill brush may be quickly and easily mounted and axially centered at the end of the handle portion of the holder, and at the same time being not only firmly and securely gripped against accidental displacement therefrom, but also so as to be rigidly held against lateral play, wobbling or like undesired movement.

The invention has for a further object to provide a holder for detachably mounting quill brushes in operative relation to the handle portion of such holder, wherein the coupling elements are compactly arranged and retained substantially within the limits of the cross-sectional area of the handle butt, so that the handle member, in size and shape, is conventional, and differs little in appearance and bulk from ordinary brush handles to which brush heads are permanently affixed.

The invention has for another object to provide a holder having quill brush coupling means comprising an axial rigid seating spike and a pair of resilient gripping jaws the members of which are respectively opposed to opposite sides of said seating spike to cooperate therewith in gripping and holding the quill shank of a brush engaged over and upon said seating spike; a sliding sleeve being arranged in connection with the butt of the holder handle to cooperate with said gripping jaws for closing the same.

Other objects of this invention, not at this time more particularly enumerated, will be understood from the following detailed description of the same.

An illustrative embodiment of this invention is shown in the accompanying drawing, in which:—

Fig. 1 is a side elevation of the novel holder with a quill brush operatively connected therewith by the novel coupling means according to this invention; Fig. 2 is a fragmentary longitudinal sectional view, drawn on an enlarged scale, showing the novel coupling means in open condition and with the seating spike and jaw elements shown in elevation; Fig. 3 is a view similar to that of Fig. 2, but showing the coupling means as

operatively arranged to engage a quill brush with the holder; and Fig. 4 is a view similar to Fig. 3 but with all parts but the seating spike in section.

Fig. 5 is a cross-sectional view, taken on line 5—5 in Fig. 4.

Similar characters of reference are employed in the above described views, to indicate corresponding parts.

Referring to the drawing, the holder device comprises a handle member 10 of the conventional tapered shape. At its butt end, said handle member is provided with a cylindrical butt-portion 11 of reduced diameter, thus providing a stop-shoulder 12 at the juncture of the handle member body and said butt-portion thereof. 15 Integral with said butt-portion 11, and extending axially from the free end thereof, is a neck-portion 13 of further reduced diameter. Extending axially outward from said neck-portion 13 is a seating spike 14, which is preferably of a form 20 tapering toward its free outer end. Preferably, although not necessarily, said seating spike 14 is a separate element, the base end portion 15 of which is affixed to said handle member structure by driving the same into an axial socket 16 which 25 extends into the neck-portion 13.

Suitably secured in connection with the neck-portion 13, so as to extend respectively along opposite sides thereof, are the anchor portions 17 of a pair of gripping jaw elements, preferably made 30 from comparatively narrow strips of resilient material, such e. g. as spring steel. Said anchor portions 17 are secured against displacement from operative assembled relation to said neck-portion 13 by any suitable form of fastening 35 means. For example, the ends of said anchor portions 17 may be provided with angular tangs 18 which are driven into and imbedded in the material of said neck-portion 13. Said anchor portions 17 extend outwardly beyond the extremity of said neck-portion 13. Each jaw element includes an outwardly inclined or oblique cam-section 19 from the outer end of which extends a jaw-section 20; the jaw-section terminating in 40 an inwardly and laterally projected gripper lip 21. 45 Preferably the gripper lips are provided with indentations 22 formed in the free margins thereof. The said anchor portions 17 exceed in length the length of the neck-portion 13, so that flexible 50 portions 17' thereof lie between the extremity of said neck-portion 13 and the junctures of the anchor portions 17 with the cam-sections 19. The junctures of the anchor portions 17 with the cam-sections 19 form at the inner sides of the jaw 55

elements secondary gripper portions 23, adapted to serve purposes presently to be described.

Secured to the butt portion 11 of the handle member 10 is a ferrule 24, the same being affixed to said butt portion 11 by annular inwardly pressed fastener beads 25. The outer end portion of said ferrule 24 extends in covering or enclosing relation over the neck-portion 13 and the anchor portions 17 of the gripping jaw elements.

- 10 Telescopically slideable upon the external surface of said ferrule 24 is a slidably manipulatable sleeve 26. When in retracted position, said sleeve is stopped in normal initial position by the abutment of its inner end against the stop-shoulder 12. When thus retracted to normal initial position, the outer end of said sleeve 26 is disposed adjacent to the outer end of the ferrule 24, thus being withdrawn from engagement with the cam-sections 19, so that the inherent resiliency or tension of the jaw elements allows the jaw-sections 20 to spread or flex apart, thus moving the gripper lips 21 to initial open or outwardly spaced relation to the intermediate seating spike 14 (see Fig. 2).
- 15 The brushes adapted to be interchangeably connected or coupled to the novel holder, comprise the brush body or head 27, the bristles of which are bound into the end of a hollow tubular quill 28 forming the shank of the brush.
- 20 To mount such form of quill brush in operative coupled relation to the holder, the jaw elements of the latter are disposed in initial open position, as shown in Fig. 2, thus exposing the seating spike 14 to receive the quill brush. The open end of the quill 28 is first thrust over the free end of said seating spike 14, whereupon the quill is slid downwardly over the latter as far as it will go.

The quill brush having been thus mounted 40 upon the seating spike 14, the sleeve 26 is slid outwardly along the ferrule 24. As the sleeve 26 is moved outwardly, its outer end will engage the outwardly flared or inclined cam-sections 19 of the jaw elements, and as outward movement 45 of the sleeve is continued along said cam-sections 19, the latter will be caused to swing inwardly, thereby, in turn moving inwardly the jaw-sections 20 until the gripping lips 21 thereof respectively engage opposite sides of the walls of the quill 28 so as to tensionally press against the latter and thereby pinch the same against the sides of the seating spike 14 (as shown in Figs. 3 and 4). The indentations 22 of the gripping lips 21 are so disposed as to receive the convexity of the quill walls, thus causing the gripping lips 21 to firmly embrace and hold the quill 28 against both longitudinal displacement from the seating spike as well as against lateral play. The inward movement of the cam-sections 19 55 also cause an inward deflection of the freely projecting parts 17' of the anchor portions 17, thereby causing the secondary gripper portions 23 to impinge upon the adjacent portions of the

quill 28, so as to further grip the same at points spaced from the gripping engagement thereof by the gripping lips 21, thus further securing the quill 28 against displacement, and also embracing the same so as to prevent any wobbling, 5 swaying or other loose movement or play of the quill brush, when operatively connected to the holder.

I am aware that changes could be made in the above described construction and many apparently widely different embodiments of this invention could be made without departing from the scope thereof as defined by the following claims; it is therefore intended that all matter contained in the above description or shown in the accompanying drawing shall be interpreted as illustrative and not in a limiting sense.

I claim:—

1. A device of the kind described, comprising a handle member having a neck-portion of reduced diameter, a seating spike projecting axially outward from said neck-portion, a brush head having a hollow shank for removable telescopic engagement over said seating spike, a pair of springy jaw elements having anchor-portions affixed to and extending along opposite sides of said neck-portion, said elements being respectively opposed to opposite sides of said seating spike, said elements terminating in gripping portions spaced longitudinally inward from the free end of said seating spike, cam-sections intermediate said anchor and gripping portions, a ferrule affixed to said handle member with its outer end portion in concentric spaced relation to and enclosing said neck-portion and the anchor portions of said jaw elements, and a slidably manipulatable sleeve on said ferrule and engageable with said cam sections to move said jaw elements relative to said seating spike, thereby to cause said gripping portions to grip and frictionally bind said brush shank to said spike.

2. In a device of the kind described, the combination with a handle member having an axially extending tapered seating spike, a brush head having a hollow shank for removable telescopic engagement over said seating spike, a pair of initially expanded springy jaw elements affixed to said handle member for projection therefrom along opposite sides of said seating spike with their free end portions terminating short of the free end of the latter, said jaw elements having longitudinally spaced primary and secondary gripper means, said jaw elements having outwardly flared cam-sections intermediate their primary and secondary gripper means, and an actuating sleeve slidably mounted on said handle member and movable to engage and contract said jaw elements to cause said primary and secondary gripper means thereof to grip and frictionally bind said brush shank to said seating spike at longitudinally spaced points.

MARTIN PERR.
